UNITED STATES PATENT OFFICE.

ADALBERT JOSEPHSON, OF NEW YORK, N. Y.

DESIGN FOR A DISPLAY-STAND.

49,520.

Specification for Design.

Patented Aug. 15, 1916.

Application filed June 20. 1916. Serial No. 104,825. Term of patent 7 years.

● *To all whom it may concern:*

Be it known that I, ADALBERT JOSEPHSON, a citizen of the United States, residing at New York city, in the county and State of New York, have invented a new and ornamental Design for a Display-Stand, of which the following is a specification, reference being had to the accompanying drawing, forming part thereof.

In the drawing, Figure 1 is an elevational

view of a display stand embodying my design; and Fig. 2 is an edge view thereof.

I claim:—

The ornamental design for a display stand, as shown.

ADALBERT JOSEPHSON.
